[57] **CLAIM**

The ornamental design for a slide, substantially as shown and described.

DESCRIPTION

FIG. 1 is a perspective view of a slide in accord with my new design,

FIG. 2 is a side elevational view of my design, the opposite side being the mirror image thereof,

FIG. 3 is a front elevational view as taken from the right of FIG. 2,

FIG. 4 is a rear elevational view as taken from the left of FIG. 2, and,

FIG. 5 is a top plan view of my slide in accord with my invention.
